UNITED STATES PATENT OFFICE.

ROBERT HARRIS, OF LONDON, ENGLAND, ASSIGNOR OF ONE-HALF TO PICTORIAL MACHINERY LIMITED, OF LONDON, ENGLAND, A BRITISH COMPANY.

PHOTOGRAPHIC COPYING, ENLARGING, AND REDUCING APPARATUS.

Application filed April 1, 1924. Serial No. 703,418.

To all whom it may concern:

Be it known that I, ROBERT HARRIS, a subject of the King of England, residing at London, England, have invented certain new and useful Improvements in Photographic Copying, Enlarging, and Reducing Apparatus, of which the following is a specification.

This invention is for improvements in or relating to photographic copying, enlarging and reducing apparatus, and relates more particularly to step-and-repeat machines in which an image is automatically maintained in focus upon a screen as the degree of enlargement is varied.

The type of step-and-repeat machine to which this invention relates comprises a unit-holder, a lens holder and an image-screen mounted upon a fixed framework, one of the said components being fixed to the framework and the other being arranged to be movable relatively thereto at such different rates as automatically to maintain an image in correct focus.

The invention has for its main object to provide improved mechanism for effecting the automatic adjustment of the focus of the image on the screen when the size of the image is varied.

According to a primary feature of this invention, a step-and-repeat machine of the type comprising an object-holder, a lens-holder and an image-screen mounted upon a fixed framework, one of the said components being fixed to the frame-work and the others being arranged to be movable relatively thereto at such different rates as automatically to maintain an image in correct focus, is characterized in that the image-screen is fixed to the framework, a movable table on the framework carries the unit-holder and lens-holder, one of which latter components is fixed thereon and the other is movable, and in the provision of means carried by the said table and operatively connected to the movable component and to the fixed framework to effect automatic adjustment of the said movable component.

According to another feature of this invention, the means mounted upon the table for moving one of the components thereon comprises a rotatable cam operatively connected with a pinion which engages a rack secured to the framework, and means for

maintaining the said movable component in contact with the cam.

According to a further feature of this invention, the teeth of the cam-pinion and rack are arranged at such an angle to the axis of the cam that the normal pitch is a standard pitch.

A further feature of the invention consists in mounting the rack on the framework so that it may be adjustable in an endwise direction. With this arrangement the focus of the apparatus may be adjusted at any time by the movement of the said rack.

For a more complete understanding of the invention there will now be described by way of example only and with reference to the accompanying drawings, one constructional form of step-and-repeat machine according to the present invention. In said drawings:

Figure 1 is a perspective view of a step-and-repeat machine according to the invention,

Figure 2 is a perspective view of part of the projector comprising a lens-holder and unit-carrier, but on a scale larger than that of Figure 1,

Figure 3 is a vertical transverse section taken through the base of the lens-holder, and

Figure 4 is a plan view of a cam.

Like reference characters designate like parts throughout the several views.

Referring to the drawings, a main frame having the form of an inverted U comprises a base A and two vertical standards A¹. A horizontally disposed framework B is mounted on three feet B¹ adjustable in height secured to the base A. This framework B extends from a line near the middle of the standards A¹ to the front of the machine beyond the front end of the base.

A stage C for an image screen is so mounted on the rear of the standards A¹ as to be movable both in vertical and transverse directions.

A table D is arranged to slide along a horizontal track provided on the top of the framework B. This table D can be moved along the said track towards or away from the screen by mechanism comprising a rack D¹ and a hand-operated pinion K¹ meshing therewith.

A projector comprises a lens-holder E, a unit-holder F and a lantern G which is

mounted on a two-wheeled trolley G^1 pivotally connected at G^2 to the unit-holder F and arranged to run on the top of the framework B .

- 5 The unit-holder F comprises a main frame F^1 adjustably attached to a base F^2 having rollers F^3 arranged to run on trackways along the top of the table D in a direction towards and away from the screen. The frame F^1 of the unit-holder has a tongue and groove connection with the base F^2 so that it can be adjusted thereon in the direction towards and away from the screen.
- 10 The lens-holder E comprises a pedestal E^1 and an open-sided hollow base E^2 which is adjustable along the table D and is normally fixed thereto by a stud as shown at E^3 . The pedestal E^1 has a tongue-and-groove connection with its base E^2 so that it can be adjusted thereon in the same direction as the frame F^1 of the unit-holder F on its base F^2 , studs being provided for securing the parts in their adjusted positions.
- 15 As shown in Figure 3, a vertical spindle H^1 is journaled in the bottom of the base E^2 and carries a cam H at its upper end in the throughway of the base. The spindle extends down through the table D into the framework B where it carries a pinion H^2 that meshes with a rack H^3 mounted on the inside of the framework B . This rack is 20 slidable in the direction of its length on the frame B and can be fixed in position by means of set-screws H^4 . The cam H , which is of the shape shown in plan in Figure 4, can extend out of the throughway of the base E^2 and contacts with a vertically disposed anti-friction roller F^4 carried on the 25 base F^2 of the unit-holder F . This base F^2 is constantly drawn towards the cam H by a cord J which runs over a pulley J^1 on the end of the table D and carries a weight J^2 movable vertically inside the framework B .
- 30 35 40 45 50 55 60 65 70 75 80 85 90 95 100 105 110 115 120 125 130

- 45 The operation of the apparatus described above is as follows:

When it is desired to enlarge or decrease the image thrown by the projector on the screen, the table D is traversed along the framework B by the hand-operated rack-and-pinion mechanism D^1, K^1 , and the unit-holder F and lens-holder E move with the table. The movement of the table D on the framework B causes the pinion H^2 and the cam H to be rotated by the rack H^3 , and the unit-holder F is thus moved relatively to the lens-holder E . The profile of the cam H is so designed that the movements of the lens-holder and unit-holder in relation to the screen maintain the image in focus in all positions of the table D . By shifting the rack H^3 endwise the apparatus may be focused at any time.

- 65 In determining the contour of the cam H the required maximum and minimum de-

gree of enlargement and the focal length of the lens in the lens-holder E are first selected. The extent of the movement of the table D towards and away from the screen can then be calculated, as also can the extent of the movement of the unit-holder F towards and away from the lens-holder E . Preferably a complete revolution of the cam H produces the required movement of the unit-holder, and thus the total lift of the cam is equal to the extent of the latter movement. Since the cam H makes one revolution in producing this movement, the pitch-circle circumference of the cam-pinion H^2 must be equal to the distance traversed by the table. It is found in practice that owing to being limited to a fixed pitch-circle circumference, a "standard" pitch very often cannot be used, "standard" pitch meaning the distance measured above the pitch circle, from the middle of one tooth to the middle of the next tooth of a pinion or rack having teeth parallel to the axis of the pinion or at right angles to the direction of length of the rack, which teeth can be cut with a standard cutter. This is because such a pinion or rack of "standard" pitch may not have the required exact whole number of teeth, without any fraction of a tooth, to correspond to the said distance to be traversed by the table. To overcome this difficulty a number of teeth is selected giving the nearest pitch to the "standard" and the teeth are arranged askew at such an angle to the axis of the pinion that the pinion has a "normal" pitch, i. e., the pitch measured perpendicular to the skew teeth, which is equal to the "standard" pitch of a like pinion having teeth parallel to its axis. Consequently, the skew gear and corresponding rack having a "normal" pitch equal to "standard" pitch can be used.

It is to be understood that various modifications may be made in the construction described above without departing from the scope of the invention as defined in the claims; for example, instead of a weight a spring may be used for keeping the roller F^4 in contact with the cam H .

What I claim as my invention and desire to secure by Letters Patent is:

1. In a step-and-repeat machine, the combination of a fixed framework, a unit holder, a lens holder and an image screen mounted thereon, one of which components is fixed and the other two arranged to be movable relatively thereto, and automatic means whereby the movement of the one movable component so automatically controls the movement of the second movable component as to maintain an image in correct focus on the screen, which means comprises a toothed rack on the framework, a cam rotatably carried by one movable component, a pinion op-

eratively connected with said cam and meshing with said rack, and means for maintaining the second movable component in contact with said cam, the teeth of which pinion and rack are arranged at such an angle to the axis of rotation of the cam that the "normal" pitch is a "standard" pitch.

2. In a step-and-repeat machine, the combination with a fixed framework, an image screen fixed thereon, a table movable on said framework towards and away from said screen, a lens-holder and a unit-holder so mounted on said table that the lens-holder is located between the screen and the unit-holder, one of which holders is fixed and the other is movable on said table, and means for automatically adjusting the movable holder in relation to the fixed holder when said table is moved along the framework, which means comprise a toothed rack on the framework, a cam rotatably carried by said table, a pinion operatively connected with said cam and meshing with said rack, and means for maintaining the movable holder in contact with said cam when the table is moved along the framework, the teeth of which pinion and rack are arranged

at such an angle to the axis of rotation of the cam that the normal pitch is a standard pitch.

3. In a step-and-repeat machine, the combination with a fixed framework, an image screen fixed thereon, a table movable on said framework towards and away from said screen, a lens-holder and a unit-holder so mounted on said table that the lens-holder is located between the screen and the unit-holder, one of which holders is fixed and the other is movable on said table, and means for automatically adjusting the movable holder in relation to the fixed holder when said table is moved along the framework, which means comprise a toothed rack mounted to be adjustable endwise on the framework, a cam rotatably carried by said table, a pinion operatively connected with said cam and meshing with said rack, and means for maintaining the movable holder in contact with said cam when the table is moved along the framework.

In testimony whereof I affix my signature.

ROBERT HARRIS.
